(57) CLAIM

The new ornamental design for a protective phone cover, as shown and described.

DESCRIPTION

FIG. 1 is a perspective left side view of the protective phone cover of the present invention;

FIG. 2 is illustrates a rear view of the protective phone invention of FIG. 1;

FIG. 3 is illustrates a front view of the protective phone invention of FIG. 1;

FIG. 4 is illustrates a left side view of the protective phone invention of FIG. 1; and,

FIG. 5 is illustrates a right side view of the protective phone invention of FIG. 1.

The dash-dot-dot line immediately adjacent to the shaded areas represents the bounds of the claimed design. The long dash-dot line showing in the figures are directed to environment and are for illustrative purposes only. The even broken line represents the stitch in the claim. None of the broken lines form part of the claimed design.
